(57) **CLAIM**

The ornamental design for a knife handle, as shown and described.

DESCRIPTION

FIG. 1 is a left side perspective view of a knife handle showing my new design;

FIG. 2 is a right side perspective view thereof;

FIG. 3 is a left side elevational view thereof

FIG. 4 is a right side elevational view thereof;

FIG. 5 is a top plan view thereof;

FIG. 6 is a bottom plan view thereof;

FIG. 7 is a rear elevational view thereof; and,

FIG. 8 is a front elevational view thereof.

FIG. 9 is a left side perspective view of an alternate embodiment of a knife handle; and,

FIG. 10 is a right side perspective view thereof.

The broken lines shown in the drawings are for the purpose of illustrating unclaimed portions of the knife handle and form no part of the claimed design.
